UNITED STATES PATENT OFFICE.

JOHN P. NEFF, OF EAST ORANGE, NEW JERSEY, ASSIGNOR, BY MESNE ASSIGNMENTS, TO AMERICAN ARCH COMPANY, OF NEW YORK, N. Y., A CORPORATION OF DELAWARE.

LOCOMOTIVE-BOILER FURNACE

1,138,068.

Specification of Letters Patent.

Patented May 4, 1915.

Application filed October 1, 1913. Serial No. 792,780.

To all whom it may concern:

Be it known that I, JOHN P. NEFF, a citizen of the United States, and a resident of East Orange, county of Essex, and State of New Jersey, have invented certain new and useful Improvements in Locomotive-Boiler Furnaces, of which the following is a specification.

My invention relates to improvements in locomotives and has particular reference to improvements in locomotive boiler fire boxes.

The object of my invention is to increase the efficiency and economy of locomotive boiler fire boxes, to provide a fire box in which the burning gases shall be delayed in their passage from the fuel bed to the flues sufficiently to permit the substantial completion of combustion before the gases escape through the flues; to provide a simple fire box construction in which a baffle wall shall be interposed between the fuel bed and the flues which baffle wall shall serve to prevent the direct flow of gases from the fuel bed to the flues; which shall also serve to eliminate sparks and cinders from the gases before they enter the flues, and which shall be provided with convenient means for removing the accumulation of sparks and cinders from the space between the baffle wall and the forward end of the firebox.

A further object of my invention is to provide a locomotive fire box, having a refractory front arch, with convenient means for removing the sparks and the cinders which accumulate upon the upper surface of the arch, said means being provided without the necessity of cutting or otherwise mutilating the fire box sheets.

My invention consists in a locomotive fire box provided with a refractory front arch and having a cinder outlet entering the space between the arch and flue sheet and extending downwardly to and through the grate and through which the accumulation of cinders and other solid particles may be removed from the space between the arch and the flue sheet.

My invention also consists in the several combinations and arrangement of parts and in the features of construction by which the above and other objects are attained and all as hereinafter described and particularly pointed out in the appended claim.

My invention will be more readily understood by reference to the accompanying

drawings forming a part of this specification and in which—

Figure 1 is a central, vertical, longitudinal section of a firebox equipped with a front arch and embodying my invention; Fig. 2 is a horizontal section of the fire box on the line 2—2 of Fig. 1; Fig. 3 is a transverse, vertical section of the fire box on the line 3—3 of Fig. 1.

The principal function of a front arch as usually installed or provided in a locomotive boiler fire box is to prevent the direct flow of the gases of combustion from the fuel bed to the flues, in other words, to baffle the gases of combustion as they are drawn upward from the fuel bed by the strong artificial drafts now employed in locomotive practice. These strong drafts tend to draw the gases of combustion out of the fire box through the flues before the combustion is entirely completed and before the burned gases have had sufficient time to give up their heat through the walls of the fire box to the water in the boiler and front arches are consequently installed to prevent these objectionable results of the strong draft and to cause the fire box gases to flow rearwardly in the fire box to and against the rear sheet and then forward along the side sheets and in contact with the crown sheet whereby they distribute their heat to and throughout the whole interior surface of the fire box in such a manner that they most efficiently give up their heat to the water in the boiler.

Another result occurring from the use of such front arches is that they tend to cause the gases of combustion to drop their burden of cinders or other unburned solid fuel particles upon the upper side of the arch before they enter the flues and these unburned particles accumulate on the upper side and back of the arch and between the arch and the flue sheet and it is necessary and desirable that this accumulation of cinders be removed before they reach such a depth that they can be drawn into or clog the flues of the boiler.

It has been the practice in some instances to provide cinder outlet openings through the lower end of the arch adjacent to the flue sheet through which these cinders and sparks could drop upon the fuel bed, but this has not proven entirely satisfactory for the reason that the accumulation of the cinders and sparks at these points on the bed of fuel serves to deaden

or dampen the fire at these points and consequently the maximum quantity of fuel cannot be consumed. It is therefore necessary from time to time to dislodge this accumulation from the fuel bed and as they lie at the extreme distance from the fire door, this dislodging operation is difficult and unsatisfactory. By means of my invention I am enabled to eliminate these undesirable features for the reason that I provide a cinder outlet, pocket or chute which enters the space between the arch and the flue sheet which outlet extends downwardly through the fire box and through the grate and is provided on its lower end with a cover which may be opened from time to time and the accumulation of cinders readily removed. The cover on the lower end is necessary to prevent the influx of air at this point.

A fire box A, as illustrated in the drawings, consists of a flue sheet a^1 at the forward end, a rear sheet a^2 provided with a fuel door or opening a^3 , a crown sheet a^4 and side sheets a^5 . Flues a^6 lead forward from the flue sheet. I have illustrated my invention in connection with a fire box provided with longitudinally arranged water circulating tubes B. In the form illustrated, the fire box is provided with four of these tubes. These tubes connect the forward and rear water legs of the boiler and are adapted to increase the circulation of water from the lower to the upper levels of the boiler and thus assist in the generation of steam and as they project through the fire and are surrounded by the burning gases they add materially to the evaporating surface of the fire box. To prevent the strong drafts which are used in locomotives at the present time, drawing the gases of combustion in a direct path from the fuel bed of the flues, I arrange a refractory arch C in the forward end of the fire box preferably supporting this arch mainly upon the water circulating tubes. This arch is made up of a number of small refractory units, preferably of a size which may be passed readily through the fire door a^3 and I form the arch bricks c^1 in such a manner that they can be arranged in transverse rows c^2 supported by and upon the several tubes. The bricks which I prefer to use are oppositely beveled at their ends and are wedgingly interposed between the tubes and I further provide bricks c^3 which fill in the spaces between the outer tubes and the side sheets of the fire box. These latter bricks are preferably arranged in an upwardly and outwardly inclined position in which position they maintain themselves by reason of their wedging shape. This arch preferably abuts the flue sheet at its forward end and projects rearwardly in the fire box to about the middle of the length of the fire box and serves to

cause the rising fire box gases to flow rearwardly in the fire box in order to get around the rear end of the arch before they rise to the crown sheet. The arch serves the further purpose of becoming highly heated and thereafter assisting in the ignition of the gases and the fuel particles. The arch being arranged in an upwardly and rearwardly inclined position, serves practically to divide the fire box A into a main combustion chamber a^7 arranged above the grate a^8 and an auxiliary combustion chamber a^9 between the arch and the flue sheet. The arch rises preferably to about the middle of the height of the group of the flues a^6 so that between the arch and the flue sheet there is a tapered space, that is, the lower part of the auxiliary combustion chamber is somewhat tapered and the fire box gases in passing over the upper end of the arch and down into the lower part of the auxiliary combustion space are caused to deposit any burden of unburned fuel particles or cinders which they have been carrying by reason of the strong draft. These particles naturally fall upon the upper or forward downwardly inclined surface of the arch and they gravitate downwardly to the space between the lower or forward end of the arch and the flue sheet and there accumulate. For the purpose of permitting the convenient and easy removal of these particles from the lower part of the auxiliary combustion chamber I provide a cinder outlet D which I preferably arrange centrally of the fire box, that is, midway between the two sides, and I secure it to the lower part of the flue sheet that is against the rear wall of the forward water leg of the fire box. The upper end d^1 of this cinder outlet or chute projects through the arch between two of the water circulating tubes and in such position that the accumulation of fuel particles readily gravitates and falls into this cinder outlet. The lower end d^2 of the cinder outlet projects through the grate space and ends below the lower end of the fire box in such position that it can be easily opened for the removal of the accumulated cinders. I close the lower end of the cinder outlet by means of a removable cover d^3 which, in its normal position, closes the lower end of the cinder outlet and prevents the admission of air at this point. As thus described, my invention accomplishes the necessary or desired results in most instances, but in some fire boxes I find it desirable to project the rear end of the arch C upwardly toward the crown sheet in order that the gases of combustion may be retained a long enough time in the main combustion chamber and in such instances I provide the upper row of arch bricks with upwardly extending projections c^4 which serve to raise the upper end of the arch somewhat above the level of the water cir-

culating tubes at this point. This upwardly extending projection, like the arch itself, extends from side sheet to side sheet and provides an efficient transverse refractory baffle in the fire box. This upwardly extending projection serves not only to more efficiently baffle the fire box gases but also to cause them to deposit the unburned fuel particles or cinders which they may be carrying, 10 for, as the gases flow over the top of this projection on the arch they are given a whirling motion which serves to forcibly throw the cinders and other particles downwardly upon the upper or forward surface 15 of the arch from which position the gases are unable to again raise the particles. The particles once having been thrown down upon the arch, they gravitate downwardly to the lower end of the arch, being assisted 20 in this movement by the jarring or trembling of the locomotive in its progress over the rails. I have illustrated the cinder outlet D as being made of material which will permit its production with relatively thin 25 walls. It will be understood, however, that I could use other materials which would necessitate the walls being somewhat thicker. The material which I prefer to use is a 30 material composed of a refractory substance and a metal so intermingled that the metal is protected against disintegration by the heat. One material of this kind is that known as corundum, which is composed 35 partly of cast iron and partly of carborundum, the cast iron serving as a matrix to

hold the particles of carborundum in position and the particles of carborundum serving to protect the matrix from disintegration. Out of material of this kind such articles as my cinder outlet can be produced 40 and will not be subject to rapid disintegration under the influence of the heat of the fire box gases.

As many modifications of my invention will readily suggest themselves to one skilled 45 in the art, I do not limit or confine my invention to the specific structures herein shown and described.

I claim:

A locomotive boiler and its contained firebox, flue-sheet, flues and grate in combination with a number of arch tubes extending upwardly and rearwardly from the lower part of said flue sheet, refractory arch bricks supported by said tubes and therewith forming 50 an imperforate baffle or arch which abuts said flue sheet and extends from side to side of the firebox, a vertical cinder chute or pocket fixed between two of said arch tubes, the upper end of said chute opening through 55 said arch and its lower end opening through said grate, and a movable closure upon the lower end of the chute below said grate.

In testimony whereof I have hereunto set my hand, this 22nd day of Sept., 1913, in 60 the presence of two subscribing witnesses.

JOHN P. NEFF.
